UNITED STATES PATENT OFFICE

2,664,701

COMBUSTION EQUIPMENT OF ROCKET MOTORS

Sidney Allen and Edward G. D. Andrews, Coventry, England, assignors to Armstrong Siddeley Motors Limited, Coventry, England

Application August 7, 1951, Serial No. 240,725

Claims priority, application Great Britain September 8, 1950

5 Claims. (Cl. 60—39.09)

1

This invention relates to a rocket motor of the kind in which liquid propellents are burnt or dissociated, and having combustion equipment including a jacketed combustion chamber through the jacket space of which one of the propellents is circulated for cooling the combustion chamber before entering the latter. Each of the propellents is, of course, supplied under pressure, either by means of a pump, or by means of pressure applied to a reservoir for the propellent.

The main object of the invention is to prevent pressure generated by evaporation or expansion of the propellent in the jacket space from causing the propellent to flow into the combustion chamber after the motor has been shut down. Otherwise, when the motor is shut down, the resulting evaporation or expansion of the propellent in the jacket space can cause a flame to be present in the combustion chamber for some time after the motor has shut down, or it can cause an accumulation of propellent in the chamber which gives rise to roughness or explosion on re-starting the motor.

According to the invention, the jacket space is connected to a pressure-responsive dump valve which is biased to the open position and closable by an applied pressure which is available only while the motor is operating; whereby, on shutting down the motor (in which case the pressure applied to the dump valve falls so as to allow it to open), the jacket space is vented so as to prevent pressure generated by evaporation or expansion of the propellent in the jacket space from causing the propellent to flow into the combustion chamber.

Preferably the dump valve is connected to the underside of the jacket, the propellent which is circulated therein passing through a check valve on its way from the outlet end of the jacket space to a spray nozzle leading to the combustion chamber. Furthermore, when the propellent which is circulated in the jacket space is delivered thereto by means of a pump, the latter may also be directly connected to the dump valve so as to apply operating pressure thereto, while the pump is working, for closing the dump valve.

In the accompanying diagrammatic drawing: Figure 1 is an elevation of a combustion equipment, of a rocket motor, with a dump valve, according to the invention, attached thereto; and

Figure 2 is a sectional elevation of the dump valve to a much larger scale, Figure 3 being a fragmentary section, to the same larger scale, of the part of the casing of the combustion equipment to which the dump valve is to be attached.

2

The invention is shown as applied to combustion equipment of the kind including a main combustion chamber 11 in which the propellents (for example, liquid oxygen or other oxidizer and a liquid fuel such as a mixture of methyl alcohol and water) are burnt.

The combustion chamber is provided with a jacket 12, and one of the propellents (e. g., the liquid fuel) is circulated through the jacket space 13 before being burnt. This propellent, delivered by a pipe 14 to the jacket space, is, after circulating round the latter, delivered by a pipe 15 through a check valve, indicated at 16, to a device 17 for spraying the fuel into the combustion chamber. The other propellent (e. g., the oxidizer) is delivered along a pipe, part of which is indicated at 18, to the spray device 17.

In the present instance the fuel is supplied from a reservoir 20 by a pump, indicated at 21, to the pipe 14; and, as will be well understood, there will be an appropriate control valve (not shown) in the pipe 14.

The dump valve 24 is formed with a passage 25 (Figure 2) adapted to be connected to the underside of the jacket space by means of the hollow nipple 26. The dump valve has a vent 27 which is placed in communication with the passage 25, i. e., with the jacket space 13, when a valve member 28 of the dump valve is raised off its seating 29, as shown in Figure 2. A spring 30 acts on a plunger 31 fast with the valve member 28 to bias it to the open position, the plunger working in a cylinder 32.

The end of the cylinder remote from the passage 25 has an inlet 34 which is shown in Figure 1 as being directly connected by a pipe 35 with the outlet of the pump 21. Thus, when the pump is started up and begins to deliver fuel, the pressure applied to the plunger 31 closes the valve member as long as the rocket motor is operating.

As previously stated, however, when the motor is shut down, in which case the pump 21 ceases to deliver fuel allowing the valve member 28 to move to its open position, the dump valve then vents the jacket space 13, and in this way pressure which would otherwise be generated in the jacket space, by the evaporation or expansion of the propellent therein, is prevented from opening the check valve 16 and allowing the propellent to flow into the combustion chamber, whereby to avoid the objections above-mentioned.

What we claim as our invention and desire to secure by Letters Patent of the United States is:

55 1. A rocket motor, of the kind in which liquid

propellents, supplied under pressure, are burnt or dissociated, including a jacketed combustion chamber, a supply pipe for delivering one of the propellents to the jacket space to be circulated therein for cooling the combustion chamber before entering the latter, a pressure-responsive dump valve connected to said jacket space, said dump valve biased to the open position, means comprising a check valve for conveying said one propellant from said jacket space to the combustion chamber, and a pipe branching from said supply pipe and applying the static pressure of the supply to close said dump valve, said static pressure available only while the motor is operating.

2. A rocket motor, according to claim 1, in which said dump valve is connected to the underside of the jacket space.

3. A rocket motor, of the kind in which liquid propellents are burnt or dissociated, including a jacketed combustion chamber, a supply pipe, a pump for supplying one of the propellents through said supply pipe to the jacket space for cooling the combustion chamber, a spray device in the chamber, a pipe connecting the jacket space to said spray device, a check valve for controlling the flow of said one propellant from said jacket space to said spray device, a pressure-responsive dump valve connected to the jacket space, said dump valve biased to the open position, and a pipe branching from said supply pipe and applying the static pressure of said pump to said dump valve whereby to close it while said pump is operating.

4. A rocket motor, of the kind in which liquid propellents, supplied under pressure, are burnt or dissociated, including a jacketed combustion chamber, means for supplying one of the propellents under pressure to the jacket space, conduit means connecting the jacket space to the combustion chamber, a check valve in said conduit means biased to closed position and adapted to be opened by the pressure in the jacket space

when said supplying means is operating, a pressure-responsive dump valve connected to the jacket space and to said supplying means, whereby the dump valve is closed during operation of said supplying means, and means for biasing said dump valve to open position when said supplying means is not working, whereby said one propellant is drained from the jacket space.

5. A rocket motor of the kind in which liquid propellents supplied under pressure are burnt or dissociated including a jacketed combustion chamber, a supply pipe, pump means for supplying one of the propellents through said supply pipe to the jacket space for cooling the combustion chamber, conduit means connecting the jacket space to the combustion chamber, a check valve in said conduit means and adjacent to the point of fuel injection to said combustion chamber and biased to closed position and adapted to be opened by the pressure in the jacket space when said pump is operating, a pressure-responsive dump valve connected to the jacket space, means for conducting said one propellant under pressure from said pump means to said dump valve for maintaining said dump valve in closed position during operation of said pump means, and resilient means for immediately opening said dump valve upon cessation of operation of said pump means.
